UNITED STATES PATENT OFFICE.

ESTELLA SOLOMON, OF PHILADELPHIA, PENNSYLVANIA.

DESIGN FOR A PORTRAIT CUSHION-COVER.

SPECIFICATION forming part of Design No. 35,958, dated June 17, 1907.

Application filed April 7, 1902. Serial No. 101,860. Term of patent 3½ years.

To all whom it may concern:

Be it known that I, ESTELLA SOLOMON, a citizen of the United States, residing at Philadelphia, in the State of Pennsylvania, have by my own industry, genius, efforts, and expense invented and produced a new and original Design, which may be called a "Portrait Cushion-Cover," for the printing of woolen, silk, cotton, or other fabrics, being a new and original ornament, pattern, and print to be printed or otherwise placed on or worked into covers for sofa-cushions, pillows, and similar articles of manufacture, of which the following is a specification, reference being had to the accompanying drawing, forming part thereof.

The figure is a drawing of one completed embodiment of my design.

As shown therein, the leading or material feature of the design consists of a number of

frames A, arranged radially about a center and intended to be stamped or worked in embroidery on the covers of sofa-cushions or pillows. The frames are connected or the interstitial spaces filled, as indicated at C, by an appropriate ornament—such as a garland, festoon, or spray of flowers—repeated between successive pairs of frames, and the frames themselves are decorated at the ends by a conventional ornament, such as a bow-knot, as indicated at B.

Having described my invention, what I claim as new, and desire to secure by Letters Patent, is—

The design for a portrait cushion-cover, substantially as shown and described.

ESTELLA SOLOMON.
